GROUND ANCHOR

Harry B. McKee, Newport Beach, Calif.

Application October 31, 1950, Serial No. 193,237

1 Claim. (Cl. 189—92)

1

This invention relates to a ground anchor for holding guys of poles, tents, and other structures, and has as a principal object the provision of an anchor particularly suited for use in trailer camps for anchoring awnings, in that such structures are temporary and require, not a permanent anchor, but one which may be easily installed and withdrawn.

Although ease of intentional withdrawal is a primary object of my invention, it is a further object thereof to provide an anchor which will hold firmly until it is intentionally withdrawn, and which may in fact be installed in duplicate to double the holding strength of any particular installation.

Many of the anchors hitherto in use for similar purposes screw into the ground and thereby soften and dislodge the earth through which they are screwed, making them relatively easy to pull out. Other anchors fit into prepared holes and then expand, which is the principle utilized in my invention, but these earlier anchors suffer the disability of having exposed screw or cam mechanisms which become clogged with earth or corroded, and also have to be buried, requiring that the holes be filled in above them when the anchors are set and then dug out again when the anchors are lifted. It is a specific object of my invention to provide an anchor which occupies all of the hole in which it is set, requiring no filling in and subsequent digging out, and which has its operating mechanism, except for the actual anchor blades, contained within its body so as to be protected from corrosive and clogging contacts.

In broad terms, my invention comprises a hollow cylinder, adapted to be placed upright in a post-hole, and carrying axially a rotatable shaft adapted to receive a guy wire and also an operating tool such as a wrench or handle. The shaft carries a plurality of anchor-blades, hinged thereto, with their free ends guided in circumferential slots in the cylinder so that rotation of the shaft in one direction causes the blades to extend outwardly through the slots, and rotation in the other direction retracts the blades within the cylinder. The shaft is arranged to be coupled at either end to the shaft of a like unit, so that two or more units may be arranged in vertical tandem, completely filling the hole in which they are sunk, so that no filling in or digging out is required, the blades of all the units acting responsively to rotation of the shaft of the uppermost unit.

2

In the accompanying drawing, illustrative of a preferred embodiment of my invention,

Fig. 1 is a vertical sectional view of my ground anchor, taken on the plane of section 1—1 of Fig. 2;

Fig. 2 is a horizontal sectional view on the plane of section 2—2 of Fig. 1; and

Fig. 3 is a horizontal sectional view on the same plane as Fig. 2, but showing the anchor blades in retracted position.

Having reference now to the details of the drawing, I have shown in Fig. 1, a cylindrical case 5 provided with end closures 6 and 7. The closures 6 and 7 have axial openings 8 through which extends a shaft 9. The shaft 9 is threaded at its upper end 10 and lower end 11, and a nut 12 is run upon the lower end 11 to serve as a support bearing for the shaft. A plate 14 is secured to the shaft 9 a little above the nut 12, and a plurality of blades 15 are pivotally secured to the plate 14 by pivot bolts 16. At the level of the blades 15, the case 5 is perforated by circumferential slots 17 equal in number to the blades, each of the blades entering and being guided by a slot respective thereto. Rotation of the plate 14 by means of the shaft 9 in a counter-clockwise direction as seen in Fig. 2 will retract the blades to the position shown in Fig. 3. Reversed rotation of the plate 14 will again extend the blades to the position of Fig. 2.

The blades 15 extend inwardly from their pivot bolts 16, as well as outwardly therefrom, their inward ends 19 being of such lengths that, as shown in Fig. 3, they will come into abutment with the outer ends of the blades next preceding them in the direction of rotation which causes retraction of the blades. Abutment of the blades, one against another, in this manner arrests the retractive movement, thus defining a position of full retraction. The outer ends of the blades 15 are of such length that when the position of full retraction is attained, as shown in Fig. 3, they will still be engaged in the slots 17 and thus will be prevented from yielding to pressure of the abutting blades. The extreme outer ends 20 of the blades are bevelled so as to be substantially flush with the outer surface of the cylinder 5 when the blades are in fully retracted position, and for this purpose the bevel 50 may be curved to conform to the surface of the cylinder. The pointed ends of the blades are thus also suited for cutting into the earth when the blades are extended, and the bevels 20 may be sharpened to further assist the cutting action.

55 The slots 17 closely fit the blades 15, so as not

only to guide them without unnecessary free motion but to prevent entry of dirt and moisture into the cylinder 5, which except for the narrow clearance of the openings 8 around the shaft 9, is otherwise sealed, and to prevent rotation of the shaft 9 beyond the position in which the blades are fully extended. For this purpose the end margins of the slots 17 are not radial to the cylinder 5 but are parallel to the chords assumed by the blades when the blades are in fully retracted position. The distance between point 17a on the inner surface of the cylinder (see Fig. 2) and 17b on the outer surface of the cylinder is just sufficient to permit the respective blade 15 to extend therethrough radially to the cylinder; the blade may turn to its retracted position with very little clearance. As the upper and lower margins of the slots 17 may have practically slide contact with the blades, it will be seen that the operating mechanism within the cylinder is afforded nearly complete protection against the ingress of dirt. The points 17a and 17b engage the sides of the blades at different distances from the pivot bolts 16, the points 17a toward which the plate 14 turns to extend the blades being slightly closer to the pivot bolts. These points of the end margins of the slots 17 will therefore bind upon the blades if an attempt is made to turn the shaft 9 in clockwise rotation as shown in Fig. 2 beyond the position therein shown, thus defining the position of maximum extension of the blades and preventing retraction from resulting from an attempt to extend the blades further. Such a limiting effect is obviously desirable when the anchor cylinder is inserted in the ground and blocks all view of the blades.

Suitable fittings are provided for installation upon the threaded ends 10 and 11 of the shaft 9 for connecting thereto the guys to be anchored, or another anchor in tandem, and to receive an operating tool. Obviously, many types of fittings would serve the above purposes, and I have shown in Fig. 1 only a very simple and effective assemblage. A nut 20, of ordinary reducer type having an external threaded portion 20a, may be placed upon the upper shaft end 10 and will receive both a wrench and a flat nut 21. The flat nut 21 has holes 21a which may receive a key wrench to turn the shaft and may then be laced with the end of a guy, not shown. An ordinary coupling 22 will serve to connect the lower shaft end 11 to the upper shaft end 10 of a tandem anchor, the fittings 20 and 21 not being installed on the upper end of the lower member of the tandem.

To install my improved anchor, a hole is first dug or bored in the ground, to a depth to receive as many anchor units as may be required and preferably so that the upper closure 6 of the upper anchor unit is just above ground level, for

drainage, and the hole will require no filling in above the unit. The hole is also preferably just undersize for the width of the cylinder or cylinders 5 so that the units when pushed into the hole will fit tightly therein. The required number of units are then connected in tandem by couplings 22, the fittings 20 and 21 are placed on the shaft of the upper unit, and the anchor units are pushed into the hole with their blades 15 fully retracted. A one-eighth turn (approximate) on the shaft of the uppermost unit will then cause the blades of all the units to expand into the ground, without, however, materially softening or dislodging the earth around them. No filling-in of the hole is necessary. A one-eighth reverse turn of the uppermost shaft will retract all the blades to permit the anchor to be raised, and no uncovering is required as the anchor extends to the ground surface. The stop at both ends of the turn is automatic. A guy will ordinarily be laced in the fitting 21 after the anchor is grounded and will be removed before the anchor is lifted.

Having described and illustrated a preferred form of my invention by way of example, I wish it understood that changes and modifications falling within the scope of the appended claims are to be considered as embodiments of the spirit of my invention and included therein.

I claim:

In a ground anchor: a cylindrical case for insertion in a prepared ground hole in substantially vertical axial position, said case having end closures and having a plurality of circumferentially extending short slots; a shaft axially mounted in said case and rotatably supported by one of said closures and extending upwardly from said case; support means carried by said shaft within said case; and blades respective to said slots pivotally carried by said support means for simultaneous and horizontal like movement, and having their outer ends guided in said slots for extension and retraction therethrough when said shaft is rotated; said slots closely fitting said blades to provide opposed fulcrums upon which said blades may swing; said blades pivoting on said support means in an orbit spaced medially between said shaft and said case; at least one of said blades extending inwardly from the pivotal axis thereof so as when retracted, to abut upon an adjacent blade while the outer ends of said blades are still engaged in the slots respective thereto, said abutting then arresting further retractive movement.

HARRY B. MCKEE.
